(57) CLAIM

The ornamental design for a foot powder dispenser as shown and described.

DESCRIPTION

FIG. 1 is an isometric view of a foot powder dispenser showing my new design;

FIG. 2 is a left elevational view thereof;

FIG. 3 is a top plan view thereof;

FIG. 4 is a bottom plan view thereof;

FIG. 5 is a front elevational view thereof;

FIG. 6 is a rear side elevational view thereof;

FIG. 7 is an isometric operational view thereof;

FIG. 8 is a front right elevational view thereof; and,

FIG. 9 is cross-sectional view thereof, taken along the line 9-9 in FIG. 5.

No claim is made to the user shown in broken lines, it is shown for illustration purposes only.

No claim is made to the indicia of a brand, name, title or the like shown in broken lines, it is shown for illustration purposes only.

No claim is made to the internal elements shown in broken lines, it is shown for illustration purposes only.
